UNITED STATES PATENT OFFICE.

JOSEPH CHARLES DEVICK, OF HELENA, MONTANA, ASSIGNOR TO AMERICAN SMCING AND REFINING COMPANY, OF NEW YORK, N. Y., A CORPORATION OF NEW JERSEY.

PALLET AND GRATE FOR SINTERING MACHINES.

Application filed October 14, 1925. Serial No. 62,369.

The invention relates to sintering machines of the Dwight-Lloyd type and more particularly to a novel arrangement of grate bars on the pallets of the endless conveyor. It is usual in such constructions to provide a conveyor of the endless type made up of tracks or pallets on which grates are mounted to convey ore from the feeding end

10 past a muffle furnace where the ore is fired or sintered to the discharge end where the ore is dumped from the conveyor into a suitable device, the operation being continuous. The pallets run over a course comprising an upper supporting track usually level and extending from the feeding end to the discharging end where the pallets fall over a suitable guiding wheel onto an inclined track which slopes downwardly 15 from the discharge end to the feeding end where the pallets are lifted by means of a bull wheel up to the upper level track.

According to the invention each pallet may be made of a suitable frame having 20 preferably four journals on which wheels are mounted to allow the pallet to run along the rails of the tracks in its course. The frame may comprise a plurality of transverse frame members which connect a pair 25 of longitudinal frame members. On the transverse frame members may be supported the grate bars which may extend longitudinally, that is, in the direction of travel of the pallet, the grate bars being loosely held 30 in position by means of a retaining bar loosely passing through holes in the bars.

According to the invention the grate bars 35 may be self cleaning. Any crust or sinter which may adhere to the bars as in the air spaces between the bars will be effectively broken loose when the pallets are shaken and jarred by their drop over the discharge end. Furthermore, the grate bars may move relatively to each other at different places 40 along the course of travel of the pallet, this arrangement causing a further self cleaning of the bars.

The longitudinal arrangement of the grate bars with the air spaces therebetween provides a more uniform distribution of air 45 passages which aids in a more uniform sintering of the ore. A further advantage of the invention is that the longitudinal grate bars may be made shorter than the trans-

verse grate bars as formerly used thereby 55 obviating difficulties due to warping, it being understood that shorter bars will not warp as much as the longer bars. Furthermore, the longitudinal arrangement of the grate bars and the dropping endwise thereof, as 60 the pallet traverses its course, will cause less breakage to grate bars than if the grate bars dropped sideways.

Another feature of the invention is the provision of grate bars in which only two 65 different kinds are necessary for equipping a pallet. The intermediate grate bars may be identical and the two end bars may be identical, the arrangement of spacing lugs 70 on the grate bars for providing the necessary air spaces eliminating the necessity of different right and left end grate bars.

Various other objects and advantages of the invention will be obvious from the following particular description of one form 75 of mechanism embodying the invention or from an inspection of the accompanying drawings; and the invention also consists in certain new and novel features of construction and combinations of parts herein- 80 after set forth and claimed.

In the accompanying drawings I have shown for purposes of illustration one form 85 of mechanism embodying the invention, in which

Fig. 1 is a plan view of a pallet according to the invention showing the relation of adjoining pallets when the pallets are traveling along the upper straight track;

Fig. 2 is a detail section on the line 2-2 of Fig. 1 showing how the grate bars are retained by the retaining bar and the mounting of the wheels on the pallet frame;

Fig. 3 is a section on the line 3-3 of Fig. 1 showing the position of alternate 95 intermediate grate bars with respect to the pallet frame when the pallet is traveling along the upper straight track;

Fig. 4 is a section on the line 4-4 of Fig. 1 showing the relation of the other 100 intermediate grate bars with respect to the pallet frame when the pallet is traveling along the upper straight track;

Fig. 5 is a bottom plan view of either the right or left end grate bar;

Fig. 6 is a section of one of the intermediate bars taken through the retaining hole thereof; and

Fig. 7 is a diagrammatic representation of an endless conveyor using pallets according to the invention.

In the following description and in the 5 claims parts will be identified by specific names for convenience, but they are intended to be as generic in their application to similar parts as the art will permit.

Referring to the drawing and more particularly to Fig. 7, the endless conveyor 10 comprises a plurality of pallets 10 running on suitable tracks and forming an endless train. A straight level upper track 3 and a straight inclined track 4 are provided between the feeding end and the discharge end. Suitable guiding devices may be provided at the feeding end and discharge end for guiding the pallets from one track to the other. At the feeding end the guiding 15 device may comprise a bull wheel 1 and a curved guide 5 while at the discharge end the guiding device may comprise a pair of curved guides 2. The bull wheel 1 which may be driven by a suitable source of power 20 lifts the pallets 10 from the lower track 4 to the upper track 3 causing the pallets to be pushed along the upper track 3 until they drop over the discharge end. The ore 25 is fed onto the conveyor at the feeding end and is discharged when the pallets drop over the discharge end, a suitable furnace arrangement (not shown) being arranged along the upper straight track between the ends.

30 Each pallet 10 may comprise a frame 18 made up of longitudinal members 11 and 12 connected by transverse end members 13 and 14 and transverse intermediate members 15 and 16. The frame 18 which may be a casting 35 may have suitable journals 19 on which are mounted wheels 20 which convey the pallet along the rails of the tracks in its course. The longitudinal members 11 and 12 are higher than the transverse members 13, 14, 15, 16 so that parts 21 and 22 thereof 40 will extend flush with the tops of the grate bars 23 as shown clearly in Fig. 2. Furthermore, the longitudinal frame members 11 and 12 may be provided with walls 24 and 25 to retain the ore.

50 Resting upon the transverse members 13, 14, 15, 16 are the grate bars 23. The grate bars are made up of an even number of like intermediate bars 27 and two like end bars 28. Each bar 23 has a retaining portion 29 near the middle thereof on its bottom side through which is a retaining hole 30. The longitudinal frame members 11 and 12 of the frame 18 have holes through 55 which a retaining bar 31 extends, said retaining bar passing loosely through the retaining holes 30 in the grate bars 23 as shown clearly in Figs. 3 and 4. Each grate bar has an annular flange 32 on its retaining 60 portion 29 around the retaining hole 30 to

protect the retaining bar 31 from the heat. These annular flanges 32 also operate to space the bodies of the grate bars to provide the necessary air space. The bodies of the bars are furthermore spaced from each other 70 and from the longitudinal frame members 11 and 12 of the frame 18 by suitable spacing lugs, the particular arrangement of which will be described hereinafter more in detail. 75

Each of the intermediate bars 27 has stop lugs 34 on its lower side between the ends thereof cooperating with the end transverse members 13 and 14 of the frame 18. These lugs are so spaced that they allow a slight endwise movement of the bars during the course of travel of the pallet. These lugs are furthermore so arranged with respect to the retaining holes 30 that when the rear lugs 34 are against the rear end transverse members 13, the retaining holes 30 in the alternate intermediate bars are centered with respect to the retaining bar 31 as shown in Fig. 4, while the retaining holes of the other intermediate grate bars are off center 80 with respect to the retaining bar, as shown in Fig. 3. This condition occurs when the pallets are traveling along the straight upper track. 85

90 Each intermediate bar 27 has a T-end and a plain end, the intermediate bars being alternately oppositely positioned so that the plain end of one bar abuts the T-end of its adjoining bars. Each end bar 28 has a T-end and an L-end which are positioned oppositely to each other, as shown clearly in Fig. 1 to cooperate with the even number of intermediate grate bars 27 to provide the necessary air spaces between the bars and the longitudinal members 11 and 12 of the frame. 95 This feature makes it possible that only two kinds of bars are needed. 100

105 The self-cleaning feature of the invention is attained as follows. As the pallets 10 are pushed up over the bull wheel 1 at the feeding end, all of the grate bars will drop back until their rear stop lugs 34 abut the rear transverse end members 13, the position being shown in Figs. 3 and 4. The 110 grate bars will substantially maintain this position until the discharge end is reached when all the bars will drop forward until their forward stop lugs 34 abut the forward transverse end member 14 of the frame as the pallet drops over the discharge 115 end. It is the custom to have the length of the course of travel of the pallets longer than the combined length of the pallets so that, as each pallet is pushed over the discharge end, it can fall by gravity a distance until 120 it hits the next pallet, this arrangement being clearly shown in Fig. 7. This shock together with the loose arrangement of the 125 grate bars operates to jar and shake loose the sinter into the place provided for it. When 130

the pallets reach the straight lower inclined track 4 they are traveling upside down, the grate bars hanging from the retaining bars. This causes a set of alternate bars to move 5 longitudinally to assume positions with their retaining holes centered with respect to the retaining bar. Furthermore, since all the bars are more or less balanced, the jarring of the pallets along their course causes additional relative movement between the grate 10 bars thereby shaking loose any crust which may still adhere. When the pallets reach the bull wheel 1 at the feed end, the other set of alternate grate bars will drop back, 15 the first set of grate bars having their stop lugs 34 already substantially against the rear end transverse members 13. This causes a second longitudinal relative movement between alternate grate bars. 20 The grate bars may be made short enough so that they can never project over the edge of the pallet frame and interfere with adjoining pallets. In other words, the relative movement of grate bars on a pallet is 25 independent of other pallets and is caused only by the movements and positions of the particular pallet.

It will easily be seen that the invention provides a pallet construction in which only 30 two kinds of grate bars are required thus cheapening the manufacture thereof as only two kinds of patterns are necessary, and decreasing the amount of storage space necessary to store replacement bars. Furthermore, the loose mounting of the bars allowing 35 endwise longitudinal movement and relative movement between adjoining bars allows them to effectively shake loose all the sinter or crust which may adhere or stick to them after passing the discharge end and which may cause burning out of the grate bars and other troubles. This last feature is attained without in any way causing any 40 larger breakage in grate bars than heretofore, the endwise movement of the grate bars being much easier on them than a lateral movement.

While I have shown and described and have pointed out in the annexed claims certain novel features of my invention, it will 50 be understood that various omissions, substitutions and changes in the forms and details of the device illustrated and in its operation may be made by those skilled in the art without departing from the spirit of my invention.

Having described my invention, I claim:

1. A pallet for an ore conveyor comprising a frame, a plurality of grate bars, and 55 means for securing said bars to said frame so that said bars may move longitudinally relatively to each other as the pallet traverses its course.

2. A pallet for an ore conveyor comprising a frame, a plurality of grate bars, and

means for securing said bars to said frame so that said bars may move longitudinally relatively to said frame as the pallet traverses its course.

3. A pallet for an ore conveyor comprising 70 a frame, a plurality of grate bars, and means for securing said bars to said frame so that alternate of said bars may move longitudinally relatively to other of said bars as the pallet traverses its course. 75

4. A pallet for an ore conveyor comprising a frame including transverse end members, a plurality of grate bars arranged longitudinally on said transverse members, each bar having a retaining portion, a retaining member secured to said frame, lugs on the bottoms of said grate bars between said end members to limit longitudinal movement of said grate bars, means for securing said retaining portions to said retaining member 80 so that alternate grate bars have their retaining portions centered with respect to said retaining member when their forward lugs are in engagement with the forward end member and other grate bars have their 85 retaining portions centered with respect to said retaining member when their rear lugs are in engagement with the rear end member, whereby said grate bars may move longitudinally relatively to said frame and to 90 each other as the pallet traverses its course. 95

5. A pallet for an ore conveyor comprising a frame having longitudinal side frame members connected by transverse end members and transverse intermediate members, 100 a plurality of grate bars arranged longitudinally on said transverse members between said side members, each bar having a retaining portion with a hole, a retaining bar passing through said end members and 105 loosely through said holes, lugs on the bottoms of said grate bars between said end members to limit longitudinal movement of said grate bars, alternate grate bars having their holes centered with 110 respect to said retaining bar when their forward lugs are in engagement with the forward end member, other grate bars having their holes centered with respect to said retaining bar when their rear lugs are 115 in engagement with the rear end member, whereby said grate bars may move longitudinally relatively to said frame and to each other as the pallet traverses its course. 120

6. A pallet for an ore conveyor comprising a frame having longitudinal side frame members connected by transverse end members and transverse intermediate members, a plurality of grate bars arranged longitudinally on said transverse members between said side 125 members, each bar having a retaining portion located between said intermediate members with a hole, a retaining bar passing through said end members and loosely through said holes, said grate bars having

flanges surrounding said holes to protect said retaining bar, lugs on the bottoms of said grate bars between said end members to limit longitudinal movement of said grate bars, alternate grate bars having their holes centered with respect to said retaining bar when their forward lugs are in engagement with the forward end member, other grate bars having their holes centered with respect to said retaining bar when their rear lugs are in engagement with the rear end member, said grate bars never projecting over the end of said frame, whereby said grate bars may move longitudinally relatively to said frame and to each other as the pallet traverses its course.

7. A pallet for an ore conveyor comprising a frame having a plurality of frame members, a plurality of grate bars arranged on said members, each bar having a retaining portion located between two of said members with a hole, a retaining bar passing through members of said frame and loosely through said holes, said grate bars having flanges surrounding said holes to protect said retaining bar, and lugs on the bottoms of said grate bars cooperating with said members to limit movement of said grate bars.

8. A pallet for an ore conveyor comprising a frame having a supporting base with upstanding side members, a plurality of like intermediate grate bars on said base each having a body and spacing lugs, like end grate bars on said base each having a body and spacing lugs, said lugs being so disposed that the bodies of said bars are spaced from each other and from said walls, and means for securing said grate bars to said frame so that said bars may move relatively to said frame as the pallet travels its course.

9. A pallet for an ore conveyor comprising a frame having a base with upstanding side members, a plurality of grate bars arranged on said base between said side members, each bar having a retaining portion with a hole, a retaining bar secured to said frame and passing loosely through said holes, said grate bars having flanges surrounding said holes, said grate bars being composed of like end bars and an even number of like intermediate bars, said end grate bars each having a body with lugs forming a T-end and an L-end, said intermediate grate bars each having a body with a plain end and lugs forming a T-end, said intermediate bars being alternately oppositely arranged and said end bars being oppositely arranged, whereby the bodies of said bars are spaced from each other and from said side members by said projecting lugs.

10. A pallet for an ore conveyor comprising a frame having a base with upstanding side members, a plurality of grate bars ar-

ranged on said base between said side members, each bar having a retaining portion, a retaining member secured to said base, means for loosely securing said retaining portions to said retaining member, said grate bars being composed of like end bars, and an even number of like intermediate bars, said end grate bars each having a body with lugs forming a T-end and an L-end, said intermediate grate bars each having a body with a plain end and lugs forming a T-end, said intermediate bars being alternately oppositely arranged and said end bars being oppositely arranged, whereby the bodies of said bars are spaced from each other and from said side members by said projecting lugs.

11. A pallet for an ore conveyor comprising a frame having longitudinal side members connected by transverse end members and transverse intermediate members, a plurality of grate bars arranged longitudinally on said transverse members between said side members, each bar having a retaining portion located between said intermediate members with a hole, a retaining bar passing through said end members and loosely through said holes, said grate bars having flanges surrounding said holes, said grate bars being composed of like end bars and an even number of like intermediate bars, said end grate bars each having a body with lugs forming a T-end and an L-end, said intermediate grate bars each having a body with a plain end and lugs forming a T-end, said intermediate bars being alternately oppositely arranged and said end bars being oppositely arranged, whereby the bodies of said bars are spaced from each other and from said side members by said projecting lugs.

12. A grate comprising a frame having a supporting base, a plurality of like grate bars on said base each having a body with a plain end and projecting lugs forming a T-end, said bars being alternately oppositely arranged, whereby the bodies of said bars are spaced from each other.

13. A grate comprising a frame having a supporting base with upstanding side members, a plurality of like intermediate grate bars on said base each having a body with a plain end and projecting lugs forming a T-end, like end grate bars on said base each having a body with projecting lugs forming a T-end and an L-end, said intermediate bars being alternately oppositely arranged and said end bars being oppositely arranged, whereby the bodies of said bars are spaced from each other and from said side members by said projecting lugs.

14. A pallet for an ore conveyor comprising a frame, a plurality of grate bars, and means for securing said bars to said frame

so that said bars may move longitudinally relatively to the frame and in substantially the direction of the course of pallet travel as the pallet traverses said course.

5 15. A pallet for an ore conveyor comprising a frame, a plurality of grate bars, and means for securing said bars to said frame so that said bars may move longitudinally relatively to each other and in substantially 10 the direction of the course of pallet travel as the pallet traverses said course.

16. A pallet for a sintering machine comprising a frame having a retaining member, a plurality of grate bars arranged on said 15 frame, each having a retaining portion, said bars having their lengths arranged in the direction of travel of said pallet, means for loosely securing said retaining portions to said retaining member whereby, when said 20 pallet is inverted said retaining portions center themselves on said retaining member to move said bars in the direction of their length relatively to said frame.

17. A pallet for an ore conveyor comprising a frame having a retaining member, a plurality of grate bars arranged on said frame each having a retaining portion loosely secured to said retaining member, abutment means to limit the movement lengthwise of said bars with respect to said frame 25 so that alternate grate bars have their retaining portions centered with respect to said retaining member when they have reached their foremost position and the other grate bars have their retaining portions centered with respect to said retaining member when they have reached their rearmost position, said retaining portions being centered on said retaining member when said pallet is inverted, whereby said grate bars 30 may move longitudinally relatively to said frame and to each other as the pallet traverses its course.

In testimony whereof I have hereunto set my hand.

JOSEPH CHARLES DEVICK.
